Joseph M. Ward.

UNITED STATES PATENT OFFICE.

ALONZO E. RHOADES, OF HOPEDALE, MASSACHUSETTS, ASSIGNOR TO DRAPER COMPANY, OF HOPEDALE, MASSACHUSETTS, A CORPORATION OF MAINE.

TAKE-UP MECHANISM FOR LOOMS.

No. 913,914.

Specification of Letters Patent.

Patented March 2, 1909.

Application filed July 7, 1908. Serial No. 442,338.

To all whom it may concern:

Be it known that I, ALONZO E. RHOADES, a citizen of the United States, and resident of Hopedale, county of Worcester, State of Massachusetts, have invented an Improvement in Take-Up Mechanism for Looms, of which the following description, in connection with the accompanying drawing, is a specification, like characters on the drawing 10 representing like parts.

This invention relates more particularly to take-up mechanism for looms, and it has for its object the production of means whereby the weaver can with one hand render 15 inoperative the take-up, detent and let-back pawls when it is desired to operate the take-up manually, such operation being readily effected by the free hand of the weaver.

My invention especially applies to that 20 form of take-up mechanism wherein a predetermined amount of let-back is permitted when the take-up pawl is released automatically from coöperation with the ratchet, and I have shown my invention embodied in 25 mechanism substantially as shown and described in United States Patent No. 729593 granted to Jamieson June 2, 1903.

Figure 1 is a left-hand side elevation of a 30 portion of a loom and its take-up mechanism substantially as in the patent referred to, with one embodiment of my invention applied thereto; Fig. 2 is a separate detail of the detent and let-back pawls, and the 35 manually operated device whereby said pawls are disengaged from the ratchet when desired.

The take-up ratchet a^3 , the train of gearing between it and the take-up roll T, the controlling rock-shaft d^x , having an attached 40 arm d connected by a slot and pin connection at d' with a link a^{17} the lower end of which is pivoted to an arm a^{15} of the take-up pawl a^2 , pivoted at a' on a bracket a secured to the lay-sword A^x ; the shipper S and knock 45 off arm g^{10} coöperating with the lower end of the shipper, to release the latter by or through the occurrence of a warp-fault, and the upturned arm f^3 fast on the shaft d^x , to turn the latter in the direction of the arrow 50 100, Fig. 1, by or through the occurrence of a filling fault, may be and are all substantially as in the Jamieson patent.

As more clearly shown in Fig. 2 the detent pawl 1 is fulcrumed on a pin 2 extended lat-

erally from the stand 3 fixed on a part of the 55 cloth-roll guide, substantially as in the patent referred to, said pawl normally coöperating with the ratchet a^3 and preventing retrograde movement thereof. Said pawl has a lateral lug 4 near its toe, which loosely 60 enters the enlarged eye 5, see dotted lines Fig. 1, of a bracket 6 secured to and depending from the arm d , so that when the latter is raised by turning of the rock-shaft d^x the 65 detent pawl will be lifted from the ratchet at the same time that the link a^{17} is lifted to throw the take-up pawl a^2 out of engagement 70 with the ratchet. Herein let-back is provided for by the pawl 7 having an elongated slot 8 through which the pivot-pin 2 extends loosely whereby when the pawls a^2 and 1 are thrown out the pawl 7 by its engagement 75 with the ratchet, and by reason of the slot 8, permits retrograde rotation of the ratchet a^3 for one, two or more teeth, as may be 80 desired.

Sometimes it is desired to operate the take-up by hand, and with three pawls to be disengaged from the ratchet it is impossible to accomplish the desired object unless the 85 weaver can with one hand control the pawls while the other hand is left free to manipulate the take-up mechanism. Herein I have provided very simple and easily operated means for throwing out the three pawls by 90 one hand.

The tail of the let-back pawl 7 is extended forward to form a lateral shelf or hand-piece 9, see dotted lines Figs. 1 and 2, and a depending ear 10 provided with a headed stud 90 11 which enters loosely an elongated slot 12 in the upper end of a releasing link 13, pivotally connected at its lower end at 14 with the take-up pawl a^2 . The let-back pawl 7 has a lateral lug 15 extended under the detent 95 pawl 1 near the toe thereof.

When the weaver desires to operate the take-up by hand he presses down the shelf 9 with his right hand, thereby elevating the toe of the let-back pawl and disengaging it from 100 the ratchet, while the lug 15 lifts the detent pawl 1 from the ratchet, and when the stud 11 engages the bottom of slot 12 the link 13 is moved down in the direction of arrow 50, Fig. 1, throwing out the take-up pawl a^2 105 against the action of spring 16. The ratchet is now free from the control of all three pawls, and the weaver with his left hand can move

the take-up backward or forward, as desired, and with perfect freedom so long as the shelf or hand-piece 9 is depressed.

When the hand-piece is released the various pawls at once return to normal position in coöperation with the ratchet.

The slot 12 provides for the slight up and down motion due to the normal operation of the take-up pawl.

10. By noting the relative position of the take-up pawl and the other two pawls 1 and 7, Fig. 1, it will be manifest that without some controlling or releasing device for all of the pawls it would be impossible to operate the 15 take-up by hand, as otherwise the weaver would need both hands to hold the pawls out of engagement with the ratchet.

The large area of the eye 5 in the bracket 6 provides for the manual release of the 20 detent pawl without interference with the means for effecting its release automatically.

Having fully described my invention, what I claim as new and desire to secure by Letters Patent is:—

25. 1. In take-up mechanism for looms, a ratchet, a take-up pawl to actuate it, detent and let-back pawls normally coöperating with the ratchet at a distance from the take-up pawl, and means to release automatically 30 said take-up and detent pawls, to permit let-back, combined with manually operated means to disengage all three of said pawls from the ratchet, whereby the take-up can be operated by hand, said manually operated 35 means including separate releasing devices for and to act upon the detent and take-up pawls, respectively.

2. In take-up mechanism for looms, a ratchet, an actuating pawl therefor, and 40 detent and let-back pawls normally coöperating with the ratchet, said let-back pawl having a releasing device for the detent pawl, combined with a manually operated actuator mounted on the let-back pawl, and a releasing 45 device for the actuating pawl, operatively connected with said actuator, operation of the latter releasing all of said pawls from engagement with the ratchet.

3. In take-up mechanism for looms, a ratchet, an actuating pawl therefor, and detent and let-back pawls normally coöperating with the ratchet, combined with a hand-piece extended from the let-back pawl, to disengage it from the ratchet, a device on 50 said pawl to effect disengagement of the detent pawl and the ratchet at such time, and a releasing connection between the hand-piece and the actuating pawl, whereby the operator can with one hand render all of said pawls inoperative and with the other hand operate 55 the take-up.

4. In take-up mechanism for looms, a ratchet, a take-up pawl to operate it, a detent pawl having a fixed fulcrum, and a let-back pawl mounted on said fulcrum and provided with a releasing lug extended under the 60 detent pawl, an extension on the let-back pawl having a lateral shelf forming a hand-piece, and a releasing link connecting the extension and the take-up pawl, depression of the hand-piece successively disengaging the let-back, detent and take-up pawls from the 65 ratchet.

5. In take-up mechanism for looms, a ratchet, a take-up pawl to operate it, a detent pawl having a fixed fulcrum, and a let-back pawl mounted on said fulcrum and provided with a releasing lug extended under the 70 detent pawl, an extension on the let-back pawl having a lateral shelf forming a hand-piece, and a releasing link connecting the extension and the take-up pawl, depression of the hand-piece successively disengaging the let-back, detent and take-up pawls from the 75 ratchet, combined with means actuated by a 80 change in the operation of the loom to effect disengagement automatically of the take-up and detent pawls from the ratchet.

In testimony whereof, I have signed my name to this specification, in the presence of 90 two subscribing witnesses.

ALONZO E. RHOADES.
